UNITED STATES PATENT OFFICE.

JOHN T. CURTIS, OF ORRVILLE, OHIO.

DUST-PAN.

No. 820,627.

Specification of Letters Patent.

Patented May 15, 1906.

Application filed February 27, 1906. Serial No. 247,626.

To all whom it may concern:

Be it known that I, JOHN T. CURTIS, a citizen of the United States, and a resident of Orrville, in the county of Wayne and State 5 of Ohio, have invented certain new and useful Improvements in Dust-Pans; and I do hereby declare that the following is a full, clear, and exact description of the same, reference being had to the annexed drawings, 10 making a part of this specification, and to the figures of reference marked thereon, in which—

Figure 1 is a perspective view. Fig. 2 is a section on line 2 2, Fig. 1.

15 The present invention has relation to dust-pans; and it consists in the novel arrangement hereinafter described, and particularly pointed out in the claim.

Similar numerals of reference indicate 20 corresponding parts in both figures of the drawings.

In the accompanying drawings, 1 represents the bottom of the dust-pan, which is formed of a size equal to the size of the dust- 25 pan designed to be constructed. The bottom 1 is formed convexo-concave, and the forward portion of the bottom is provided with the flange 2, which flange diverges from the forward edge of the bottom and extends 30 rearward a short distance, and the rear edge of the flange 2 is provided with the downturned portion or flange 3, which flange is secured in any convenient and well-known manner to the bottom 1.

35 In the manufacture the flanges 2 and 3 may be and preferably are formed integral with the bottom and folded into the position illustrated in the drawings, by which arrangement the forward portion of the dust-pan 40 constitutes an integral structure. The side plates 4 are formed by bending portions of the bottom, and also the back 5 is formed by bending a portion of the bottom plate. This construction, however, is common in dust- 45 pans and needs no detailed description. The object and purpose of forming the bottom convexo-concave is to provide for contact-points only at the extreme forward edge and the extreme back edge of the dust-pan 50 proper, by which arrangement the extreme point of the dust-pan will at all times lie in contact with the floor or carpet. An-

other object and purpose of forming the bottom convexo-concave is to form an elevation between the flange 3 and the back plate 5, 55 thereby assisting in holding the material swept onto the dust-pan. The flange 3 also prevents the material swept onto the bottom of the dust-pan from accidental displacement therefrom; but by forming the bottom convexo-concave two elevations are presented 60 against the removal of the material from the dust-pan.

In use it is desirable to prevent the dust-pan from moving backward during the time 65 the material is being swept onto the dust-pan, and to provide against this backward movement the points 6 are provided, which points are formed short and inclined rearward, so that they will have a tendency to pierce the 70 floor or carpet when backward pressure is brought against the dust-pan, and thereby hold the dust-pan against any accidental movement. The points 6 may be and preferably are formed separate and attached in 75 any convenient and well-known manner.

If desired, the dust-pan proper may be provided with a handle, such as 7, which handle may be of any desired length.

Having fully described my invention, what 80 I claim as new, and desire to secure by Letters Patent, is—

As an improved article of manufacture, a dust-pan, provided with a convexo-concaved bottom, the upper or convexed face constituting the floor of the pan and the under or concaved portion the contact portion, a diverging flange extended upward and rearward over a part of the convexo-concaved bottom, a flange extended downward from 85 the upper rear edge of the rearward-extended diverging flange, and said flange located forward of the uppermost point of the convexo-concaved bottom, and contact-points located 90 at the rear edge of the bottom, substantially 95 as and for the purpose specified.

In testimony that I claim the above I have hereunto subscribed my name in the presence of two witnesses.

JOHN T. CURTIS.
